DESIGN FOR A HANDKERCHIEF OR SIMILAR ARTICLE

Michael S. Sutton, Brooklyn, N. Y.

Application February 25, 1936, Serial No. 61,349

Term of patent 7 years

To all whom it may concern:

Be it known that I, Michael S. Sutton, a citizen of the United States and a resident of Brooklyn, New York, in the county of Kings and State of New York, have invented a new, original, and ornamental Design for a Handkerchief or Similar Article, as shown, of which the following is a specification, reference being had to the accompanying drawing, forming a part hereof.

The figure of the drawing shows substantially a quarter section of the handkerchief constituting my design, the other three-quarters being

identical with that illustrated and arranged in proper relation to complete the handkerchief.

The dominant features of my design are characterized by intersecting borders of open weave, the borders being defined by smaller borders to each side of the open weave made of corded threads.

I claim:

The ornamental design for a handkerchief or similar article as shown and described.

MICHAEL S. SUTTON.
